UNITED STATES PATENT OFFICE

140,573

DESIGN FOR A SHOE

Jacob Sandler, Brookline, Mass., assignor to Atlantic Footwear & Pattern Co., Boston, Mass., a copartnership

Application December 13, 1944, Serial No. 116,872

Term of patent 14 years

(Cl. D7—7)

To all whom it may concern:

Be it known that I, Jacob Sandler, a citizen of the United States residing at Brookline, in the county of Norfolk and State of Massachusetts, have invented a certain new, original, and ornamental Design for a Shoe, of which the following is a specification, reference being had to the accompanying drawing, forming part thereof.

In the drawing,

Fig. 1 is a perspective view of the right side of a shoe showing my new design; and

Fig. 2 is a perspective view of the left side of the shoe shown in Fig. 1.

I claim:

The ornamental design for a shoe, as shown.

JACOB SANDLER.
